(57) **CLAIM**

The ornamental design for a camping trailer, as shown and described.

DESCRIPTION

FIG. 1 is a front, left and top perspective view of a camping trailer, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof;

FIG. 10 is an enlarged view of portion of FIG. 1 thereof;

FIG. 11 is an enlarged view of portion of FIG. 1 thereof; and, FIG. 12 is a perspective view in the using configuration of FIG. 1 thereof.

The dot-dash broken lines depict the boundaries of the enlargements that form no part of the claimed design,

1 Claim, 12 Drawing Sheets
